#1314 Pat'd.
J. GETZ, DESIGN 280
For Flour Barrels.

Fig. 3306

Fig. I

Jan 15 1871
3306

Fig. II

Witnesses:

H. J. Chamberlain

J. H. Donley

J. Getz, Jr.
J. Braun & Co
Atg

JACOB GETZ, OF BUFFALO, NEW YORK.

Design No. 3,306, dated January 5, 1869.

DESIGN FOR A TRADE-MARK.

The Schedule referred to in these Letters Patent and making part of the same.

To all whom it may concern:

Be it known that I, JACOB GETZ, of the city of Buffalo, in the county of Erie, and State of New York, have invented a new Design for a Trade-Mark for flour-barrels, of which the following is a full, clear, and exact description, reference being had to the accompanying drawings, making a part of this specification.

Figure 1 shows a monogram, embracing the initials of the names of J. Getz & Co., with peculiar ornamentation.

Figure 2 shows the same, as applied to a flour-barrel, in combination with the painted hoops thereon.

My invention consists in combining the initials of the firm of J. Getz & Co. into a monogram, as shown in the drawings, with a representation of a sheaf of wheat at one side, the whole surrounded with an ornamental beaded line, the whole device being in oblong form, and designed as a stamp or ornamental trade-mark, to be placed on the side of a flour-barrel or barrels.

My invention further consists in painting the hoops of flour-barrels either with a single color—red, for example—or combining various colors, as shown in fig. 2, for the purpose of distinguishing either the barrel, or the brand of flour contained therein, and acting as a trade-mark, to be used with or without (as may be preferred) the monogram and ornamentation described herein.

In the drawings—

A represents the ordinary flour-barrel, with hoops a a a painted in different colors, and the monogrammatic design B placed on the side of the barrel, where I preferably put it, though I do not desire to confine myself to putting it on the bilge or centre, but in any suitable place on the side, and not on the head, as is customary.

As a miller, and manufacturer of flour-barrels, I design to distinguish the barrels made and sold by my firm, by painting the hoops of the barrels in any desired color, so that at a glance they may be at once recognized as one make of barrels, or containing a grade of flour that will become well known and popular by so distinctive a mark as a painted hoop, which I believe has never before been used for a similar purpose.

It is well known that "brands" on flour-barrels are imitated at will by manufacturers, and great loss to the original user and designer accrues thereby, for as soon as his barrels obtain a reputation, they are counterfeited by others, who put inferior qualities of flour in their barrels, and destroy the prestige of the brand thereby.

By painting the hoops of my barrels, in connection with the within-described monogram of my firm, I expect and hope to obviate this counterfeiting and difficulty, but if purchasers desire to obtain the barrels with painted hoops only, and without the monogram, I desire to be protected in either method.

The object of using different colors, is merely to distinguish the different brands of flour contained in the barrels. For example, if the hoops are painted red, that would signify No. 1 St. Louis white wheat, and the barrels would be known as our "red-hoop No. 1 St. Louis." If painted blue, it would indicate No. 1 Kentucky white wheat; or if painted in two or more colors, it would stand for another grade, and so on until by successful counterfeiting we were obliged to change the mark and brand.

I am well aware that barrels have sometimes been painted all over in blue, red, or other colors, but merely to protect them from the weather, or, as in oil-barrels, to stop the pores, and protect them from the weather and shrinkage, or, as in sugar-barrels in stores, to make them look neater, but I have never known of the hoops being painted for the purpose I describe.

Believing myself to be the first to think of and use the idea of painting the hoops of a flour-barrel as an ornament to quickly strike the eye and distinguish my manufacture,

I therefor claim as my invention, and desire to secure by Letters Patent—

A flour-barrel, having marked, painted, printed, or stamped thereon, the design herein described; also, having the hoops of the same painted or colored, either in one or more colors, for the use and purpose herein set forth.

In witness whereof, I have hereunto signed my name, in the presence of two subscribing witnesses.

JACOB GETZ.

Witnesses:

J. R. DRAKE,
ALBERT HAIGHT.